CLAIM

The ornamental design for a reconfigurable toy vehicle, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front elevation view of a reconfigurable toy vehicle showing our new design;

FIG. 2 is a rear elevation view thereof;

FIG. 3 is a left elevation view thereof;

FIG. 4 is a right elevation view thereof;

FIG. 5 is a top plan view thereof;

FIG. 6 is a bottom plan view thereof;

FIG. 7 is a front perspective view thereof;

FIG. 8 is a top perspective view thereof;

FIG. 9 is a bottom perspective view thereof;

FIG. 10 is another bottom perspective view thereof;

FIG. 11 is a front elevation view of the design shown in FIGS. 1-10 in a robotic humanoid configuration;

FIG. 12 is a rear elevation view thereof;

FIG. 13 is a right elevation view thereof;

FIG. 14 is a left elevation view thereof;

FIG. 15 is a top plan view thereof;

FIG. 16 is a bottom plan view thereof;

FIG. 17 is a rear perspective view thereof;

FIG. 18 is a front perspective view thereof;

FIG. 19 is a bottom perspective view thereof; and,

FIG. 20 is another bottom perspective view thereof.

(Continued)

The design is reconfigurable from a vehicle to a robotic humanoid.
